Charles B. Moran
By George Curran Atty.

UNITED STATES PATENT OFFICE.

CHARLES B. MORAN, OF HORSE CAVE, KENTUCKY.

FOOTBALL APPARATUS.

Application filed October 30, 1922. Serial No. 597,725.

To all whom it may concern:

Be it known that I, CHARLES B. MORAN, a citizen of the United States, residing at Horse Cave, in the county of Hart and State of Kentucky, have invented new and useful Improvements in Football Apparatus, of which the following is a specification.

This invention relates to an apparatus for the instruction and practice of football.

10 One object of my invention is to provide a structure whereby a plurality of tackling dummies may be distributed in various positions over an area of a playing field and thus permit placing the dummies in the positions of players on a team when lined up for either attack or defense, or in other positions during the course of a play, in order that instruction and practice may be had in tackling, interference, running in broken fields, studying and meeting the formations of various plays and other conditions encountered in an actual game of football.

Another object of my invention is to 25 make the dummies shiftable or movable so that their positions may be changed as desired and thus give practice in interference by moving them into a play after it has started and while in movement.

30 A further object of my invention is to provide an arrangement for positioning certain of the dummies in the various positions taken by the ends on a team in defense and thus give practice in meeting a waiting end, a one step end, a two step end, and a charging end.

The invention consists further in the matters hereinafter described and more particularly set forth in the appended claims.

In the accompanying drawings—

40 Figure 1 is a perspective view of an apparatus constructed in accordance with my invention with dummies arranged thereon;

45 Fig. 2 is a plan view of a number of the wires showing the manner in which the diverging wires at one side of the apparatus are run to a single point or ring;

Fig. 3 is a view showing the multiple pulley block provided at said ring;

50 Fig. 4 is a front view of the apparatus shown in Fig. 1;

Fig. 5 is a view of one of the upright posts to show the manner in which several of the wires are attached and arranged; and

Fig. 6 is a front view of a pulley block for a dummy and showing the releasable hook 55 to be hereinafter described.

As shown in Fig. 1, the apparatus comprises four corner posts 1, 1, and two sets of side posts 2, 3, 4, 5, and 6, arranged in the order named on each side of the device. 60 The posts 1, 2, 3, and 4 at each side of the apparatus are connected together adjacent their upper ends by a wire 7. Extending between the posts 4, 4 is a wire 8 and below this is another wire divided into two end sections 9, 9 and a mid-section 10. The end sections 9, 9 are connected with the mid-section by rings 11, 11. To support the divided wire from the wire 8, a loop 12 is between them, as shown. 70

From each ring 11 diverge wires 13, 14, and 15. These are connected with the associated posts 1, 2, and 3, respectively, in the order named. These diverging wires, together with the wires 9, 9, provide two sets of diverging wires, one set at each side of the apparatus, and each set consisting of the same number of wires, namely, four, in an apparatus made as shown in Fig. 1. For the wires of each set, I provide tackling dummies 16, 17, 18, and 19, one on each wire, as shown. Arranged substantially parallel with the divided wire is a wire 20. This is continuous from end to end and extends between the posts 4, 4. This wire serves as a 80 trolley and support for tackling dummies 21, 21. The wire 20 is spaced from the divided wire so that the pulley blocks of the dummies 21 may be moved along the wire 20 without interference by said divided wire. 90

Extending between the posts 5, 5 is a cross-wire 22 to support one or more dummies 23. Extending between the posts 6, 6 is a cross-wire 24 to support one or more dummies 25, 25. The posts 4, 5, 6 and the 95 end post 1 adjacent the latter at each side of the apparatus are connected adjacent their upper ends by a wire 26. Extending between the wires 26, 26 is a cross-wire 27 to support a dummy 28. This wire 27 is connected with the side wires 26 between the posts 5, 6, as shown.

At front and rear of the apparatus, the end posts 1 are connected by cross-wires 29, 29, as shown. On the last mentioned one is 100 a dummy 30. The end posts 1 are also con-

nected together diagonally across the apparatus by diagonally arranged wires 31, 31. These meet at a ring 32.

The cross-wires are maintained sufficiently 5 taut and the posts are held upright by outside guide wires 33, 33, secured to ground anchors 34, 34, as shown in Fig. 4.

For each of the dummies there is a pulley 10 block of the form shown in Fig. 6. As there illustrated, the block 35 carries a grooved sheave or pulley 36 to roll on one of the wires. The lower end of the block 35 carries a block 37, in which is a swivel hook 38. The block 37 is pivoted or hinged at 39 15 on one side to the pulley block 35 and releasably engaged on the other side with said pulley block by a detachable connection 40. This enables the pulley block to be readily removed from and placed on a wire, thus permitting 20 positions of the dummies to be changed from time to time as may be desired.

The apparatus shown and described is 25 used in the following manner. In Fig. 1, I have shown the dummies arranged for defense. The players are lined up in the usual formation for attack in front of the dummies 21. These are suitably spaced apart on the wire 20 in a manner to provide 30 interference for the guards and tackles on the attacking team. Back of them are placed dummies representing full, half backs and quarter backs.

The ends of the defending team are 35 represented by the dummies 16 to 19 at the sides of the apparatus. These initially are all in position adjacent their respective posts 1 to 4, as shown in Fig. 1. Assuming for 40 illustration that the play is going around right end, viewing the apparatus set up as in Fig. 1. With four dummies 16 to 19 at "right end" any one can be pulled in on its wire to interfere with the play just as a real end would do. Four dummies 16 to 19 45 are used to illustrate four different attacks by an end as taught and coached on defense in football. There is what is known as a "waiting end." This is taught by running in the dummy 19 on its wire 20 to the position 50 usually taken by a real end, and have the dummy wait the play.

A one step end is another position of defense. By this is meant, the end charges in one step and waits. This is accomplished by 55 running the dummy 18 in on its wire 15. A "two step" end would be answered by running the dummy 17 in on its wire 14. A "straight charging" end would be an end charging straight in from his position and cover from one to four steps before meeting 60 the play. This is done by running the dummy 16 in on its wire 13. By having the wires diverging, the dummies can reach their positions in the shortest space of time and be operated from the most convenient points.

65 After the necessary practice has been had

with the "end," the play may proceed further, that is, beyond the line of dummies 21, 21, and there interference met with by the use of the dummies 23, 25, 28, and 30. These may be moved along their wires to such positions as the coach may require to best illustrate the play at hand.

The apparatus shown and described permits the use of a great number of dummies 70 and these, by the releasable pulley blocks 35, 75 may be easily moved from wire to wire to present such conditions of play as the coach may wish to show. With a plurality of dummies hung up it is possible to have a 80 number of players tackling at the same time. It is also possible to have the dummies moving at almost any speed while being tackled and thus instruct in flying tackles and also teach players "judge of distance." In this 85 connection, tackling the dummies 16 to 19 on the inclined or converging wires 9 to 13 enables instruction to be had in tackling from different angles.

By having a plurality of dummies and 90 being able to arrange them in many and different positions over a given area of the playing field, instruction may be had in running in a broken field.

With the dummies suspended by pulley 95 blocks and on wires, I can also instruct in "interference" work. This can be done by moving the dummies successively into positions to interfere with the play as it progresses along the field. The dummies may 100 take the place of the "scrub" team in practice and thus save the players from injury by not having them tackle each other.

The apparatus described, when used to 105 instruct in matters of offense, has the dummies lined up as if carrying the ball and by moving certain of the dummies on their wires plays may be explained, how blocked, etc.

This apparatus makes it possible to practice and study the various combinations of 110 plays, both attack and defense, and further enables trying out the plays of opposing teams in advance of the actual games with them in order to have the advantage in being familiar with their style and character 115 of play.

The side wires 26, 26 are lower than the 120 wires 7, 7 to allow the diagonal wires 31 to pass over them to the rings 11. All of the wires are arranged high enough to allow a forward pass to be made. For each set of dummies 16 to 19, I provide a pulley block 41, as shown in Fig. 3. This has a plurality of sheaves 42, 42, one for each dummy. The block 41 hooks over the associated ring 11, and cables *a* to *d* are trained over the sheaves therein. These cables are connected with the respective dummies and have their free ends accessible for moving them. Each post has a base plate 43 provided with 125

pointed studs or prongs 44 to enter the ground and hold the post from slipping thereon. For shifting the other dummies 21, 23, etc., cables may be attached to them and 5 worked from the side lines of the apparatus.

While I have shown and described herein in detail an apparatus of my invention, it is of course to be understood that the details of construction and arrangement of 10 parts shown and described may be variously changed and modified without departing from the spirit and scope of my invention.

I claim as my invention:

1. An apparatus for the practice of football, comprising a plurality of tackling dummies, and a plurality of cooperative guiding means for distributing said dummies to various playing positions over a playing field.

2. An apparatus for the practice of football, comprising a plurality of tackling dummies, and a plurality of cooperative guiding means for distributing said dummies to various playing positions over a playing field,

25 certain of the dummies representing ends on a team, the guides for the end dummies permitting the shifting of said dummies into a number of playing positions.

3. An apparatus for the practice of football, comprising a plurality of tackling dummies, a plurality of cooperative guiding means for distributing said dummies to various playing positions over a playing field, certain of the dummies representing ends 35 on a team, the guides for the end dummies permitting the shifting of said dummies into a waiting end, a one step end, a two step end, and a charging end.

4. An apparatus for the practice of football, comprising a plurality of tackling dummies, a plurality of cooperative guiding means for distributing said dummies to various playing positions over a playing field, certain of said guiding means permitting 45 a plurality of said dummies to be positioned side by side in a row, and certain others of said guiding means permitting other dummies to be positioned at opposite ends of said row to represent the ends of a team.

5. An apparatus for the practice of football, comprising a plurality of tackling dummies, a plurality of cooperative guiding means for distributing said dummies to various playing positions over a playing field, 55 certain of said guiding means permitting a plurality of said dummies to be positioned side by side in a row, and certain others of said guiding means permitting other dummies to be positioned at opposite ends of said row to represent the ends of a team, said last-named guiding means permitting the individual shifting of said end dummies into various playing positions.

6. An apparatus for the practice of football, comprising a plurality of tackling

dummies, and a plurality of cooperative guiding means for distributing said dummies to various playing positions over a playing field, and individual means connected to certain of said dummies for moving the same 70 along the associated guiding means.

7. An apparatus for the practice of football, comprising a plurality of tackling dummies, and a plurality of cooperative guiding means for distributing said dummies to various playing positions over a playing field, and individual means connected to certain of said dummies for moving the same 75 along the associated guiding means, said moving means being actuated from points outside of the playing field.

8. An apparatus for the practice of football, comprising a plurality of wires and tackling dummies suspended therefrom, said wires being arranged in a manner permitting the dummies to be distributed in various positions over an area of a playing field.

9. An apparatus for the practice of football comprising a plurality of wires and tackling dummies suspended therefrom, said wires being arranged in a manner permitting the dummies to be distributed over an area of a playing field, said wires permitting the shifting of said dummies so that the positions thereof may be changed.

10. An apparatus for the practice of football, comprising upright corner and side posts, wires extending across the apparatus between said posts, a plurality of tackling dummies, and pulley blocks on said wires for suspending the dummies therefrom and permitting the shifting of said dummies on said wires.

11. An apparatus for the practice of football, comprising upright corner and side posts, wires extending across the apparatus between said posts, a plurality of tackling dummies, and pulley blocks on said wires for suspending the dummies therefrom and permitting the shifting of the dummies on said wires, said pulley blocks being releasably engaged with said wires so that the dummies may be removed therefrom and placed on other wires.

12. An apparatus for the practice of football, comprising a plurality of substantially parallel cross-wires, a plurality of wires diverging outward from one of said cross-wires on each side of the apparatus, upright corner and side posts for said cross and diverging wires, a plurality of tackling dummies, at least one on each of said wires, and pulley blocks for suspending said dummies from said wires and permitting the same to be shifted thereon.

In testimony that I claim the foregoing as my invention, I affix my signature this 26th day of October, A. D. 1922.

CHARLES B. MORAN.
